The schedule referred to, in these Letters Patent and making part of the same.

To all whom it may concern:

Be it known that I, Henry G. Thompson, of the City, County, and State of New York, have invented or produced a new and original design for a pattern to be inwrought into Three ply Ingrain and other Carpeting in colors similar to those painted on the drawings accompanying this Specification or in other colors substituted in the place of those painted on the drawings herewith; and I do hereby declare that the drawings accompanying this Specification, do give and convey to any one skilled in the art of Carpet weaving, a more defined and thorough description of the nature of my invention than it is in the power of language otherwise to convey, sufficient to enable any one skilled in the art of Carpet weaving to use my invention.

What I claim as my invention and desire to secure by Letters Patent, is the configuration of the design herunto annexed when made by being inwrought into Three ply Ingrain or other Carpeting in the form similar to the drawings accompanying this Specification.

Witnesses.
